ATTORNEY

UNITED STATES PATENT OFFICE.

ABRAHAM J. KELLER, OF NEW YORK, N. Y.

DRAPERY-HOLDER.

1,291,015.

Specification of Letters Patent. Patented Jan. 14, 1919.

Application filed April 23, 1918. Serial No. 230,265.

To all whom it may concern:

Be it known that I, ABRAHAM J. KELLER, a citizen of the United States, residing at New York city, in the county of New York and State of New York, have invented certain new and useful Improvements in Drapery-Holders, of which the following is a specification.

This invention is a drapery holder more particularly adapted for holding curtains or other window drapery in a fixed position, either for draping purposes or for retaining the curtain or drapery out of the way.

One object of the invention is to provide a holder that will effectively retain a curtain or other drapery at the side of the window opening or adjacent the frame.

Another object of the invention is to provide a holder that will permit a quick release of the curtain or drapery when it is desired to remove it or to rearrange the folds thereof.

Still another object of the invention is to provide a holder that is simple and strong in construction, easily and quickly applied, and one that will present a neat and unobtrusive appearance.

Broadly stated, the invention comprises an L-shaped bracket adapted to be secured to the window frame or other corner, one end of the bracket having hingedly connected thereto a curved drapery retaining loop, and a spring catch for removably holding the loop in a closed position.

One practical form of construction and assembly upon the corner of a window frame will be described and illustrated in the accompanying drawing, in which:

Figure 1 is a perspective view showing the holder applied to a corner, and

Fig. 2 is a sectional view showing the loop attached to a corner and also showing the loop in dotted lines when moved to an open position.

In the preferred embodiment about to be described there is provided an L-shaped bracket having the limbs 5 and 6 that preferably extend at right angles to each other. The limb 5 is provided with suitable holes so that fastening means such as the screws 7 may pass therethrough for holding the bracket to a corner piece 8. The limb 5 adjacent its juncture with the limb 6 is provided with a spring catch 9. This catch may be secured to the limb 5 in any suitable way, one of which is indicated by the rivets 10.

A catch 9 projects outwardly beyond the limb 6 and may be provided at its free end with a suitable engaging portion 11 which may be rounded or, as is shown, pointed to engage in a recess. This catch 9 is preferably formed of resilient material so that the engaging point 11 may spring into and out of engagement with a recess. The limb 6 is formed at its free end to provide a hinge joint. The pintle or pin thereof being indicated at 12. To coöperate and complete the hinge the curved drapery retaining loop 13 is provided with one portion of a hinge.

When the pin 12 connects the two portions of the hinge together, the loop 13 is then hingedly connected and is free to rotate around this pin as shown in dotted lines in Fig. 2. The hinge portion as formed upon the limb 6 is provided by bending the free end into a cylindrical form and then cutting away suitable portions to provide for the hinge engagement with the loop 13. The loop 13 as shown is curved or has a semi-circular form, and the free end 14 of the loop 13 is adapted to engage and contact with the limb 6 where it joins the limb 5. The loop 13 near its free end 14 may be provided with suitable coöperating means such as the hole or recess 15 for engaging with the point 11 of the spring catch 9.

As shown in Fig. 1, the loop is in a closed position and a curtain or other drapery is shown by dotted lines as indicated at 16. This gives the general idea of how the loop 13 will retain drapery in a fixed position and will also provide for its rearrangement when desired. The catch 11 may be provided at the point indicated at 17 with a finger engaging element. This will provide for withdrawing the point 11 from its engagement with the recess 15, whereupon the loop 13 may be readily swung back to the dotted line shown in Fig. 2.

From the above description it will be noted that the holder is of very simple construction and presents a neat appearance. By employing the catch 9 it will effectively retain the loop in a closed position against accidental opening. At any time it is desired to release the curtain or to rearrange the drapery 16, the catch may be withdrawn from engagement with the loop 13, whereupon the drapery may be changed as desired. After the changes have been made the loop 13 may be swung back and will automatically engage with the catch 9 and the point 11.

2
will seat in the hole 15 and the loop be retained in its closed position.

The foregoing description and the drawings have reference to what may be considered the preferred, or approved, form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by Letters Patent is:—

15 A drapery holder comprising a plate having one end forked to provide two arms which are bent back to form two spaced eyes on the rear of the plate, a catch secured to

the opposite end of the plate, a curved drapery retaining loop, said loop having an eye 20 formed on one end and adapted to be received between the eyes of the plate and the opposite end provided with an opening adapted to be engaged by the catch, and a pin adapted to pass through the eyes on the 25 plate and the loop, the loop being adapted to extend across the front of the plate and to have its free end engage the end of the plate.

In testimony whereof I affix my signature 30 in presence of two witnesses.

ABRAHAM J. KELLER.
